UNITED STATES PATENT OFFICE

153,263

DESIGN FOR A COAT

Benjamin Chalk, New York, N. Y.

Application October 29, 1948, Serial No. 149,390

Term of patent 3½ years

(Cl. D3—4)

To all whom it may concern:

Be it known that I, Benjamin Chalk, a citizen of the United States of America, residing in New York, county of New York, and State of New York, have invented a new, original, and ornamental Design for a Coat, of which the following is a specification, reference being had to the accompanying drawing, forming part thereof.

Fig. 1 is a front view of a coat, showing my new design.

Fig. 2 is a rear view thereof.

I claim:

The ornamental design for a coat, substantially as shown.

BENJAMIN CHALK.
